United States Patent Office

Des. 201,583
Patented July 6, 1965

201,583

BOTTLE

James A. Shepler, Toledo, Ohio, assignor to Owens-Illinois Glass Company, Toledo, Ohio, a corporation of Ohio

Filed Dec. 2, 1964, Ser. No. 82,878

Term of patent 14 years

(Cl. D58—6)

FIG. 1

The back and the sides not shown are the same as the front shown. The characteristic features of this design reside in the configuration shown in full lines on the drawing.

I claim:

The ornamental design for a bottle, substantially as shown and described.
